Application February 11, 1944, Serial No. 521,932

17 Claims. (Cl. 250—20)

1

This invention is directed to superregenerative receivers including an arrangement for controlling an operating characteristic thereof, such as band-width or sensitivity characteristic. A superregenerative receiver, as is well understood in the art, comprises an oscillator which periodically quenched at a frequency which is much less than that of the generated oscillations and more than double the modulating frequency of the signal to be received. Such a receiver may have at least two distinct modes of operation determined largely by the operating potentials applied thereto and the quenching action. In one, designated the linear mode, the quenching action is such that the oscillations generated in each quench cycle are quenched or stopped before attaining saturation amplitude. In the other, or logarithmic, mode the generated oscillations are permitted to reach saturation amplitude in each quench cycle. In either case, a receiver is characterized by a high gain and the amplitude of the output signal derived therefrom in any quench cycle varies with the amplitude of the exciting signal which initiates the oscillations generated in the particular quench cycle. The receiver is further characterized by the fact that during quiescent intervals, when no desired signals are being received, oscillations are initiated by the noise signals present in the receiver circuit, resulting in an output signal of relatively low amplitude. Such a receiver is subject to a wide range of applications and, in the usual case, either of the above-described modes of operation may be utilized. However, in any installation it may be desirable to provide a control arrangement for controlling the receiver band-width or sensitivity characteristic, or both, with variations in operating conditions.

Arrangements for controlling the operating characteristics of a receiver are known in the art but are generally directly coupled to circuit elements included within the signal-translating channel of the receiver. For example, in order to obtain a band-width control, it has been proposed to utilize a control arrangement directly coupled to an adjustable selector system included in the signal-translating channel and effective, in some cases, to adjust the band-pass characteristic of the selector system in accordance with the intensity of received desired signals. Additionally, it has been proposed to use an automatic volume control or A. V. C. system directly coupled to one or more signal-translating stages of the receiver for the purpose of obtaining a sensitivity control. While these arrangements are generally

2

satisfactory, in some installations it may be desirable effectively to isolate the control arrangement from the signal-translating channel of the receiver. This is especially true in receivers of the superregenerative type where optimum operating conditions are obtained through such an isolation, as will be described presently.

Prior art control arrangements designed specifically for application to superregenerative receivers generally comprise a system which rectifies a selected portion of the receiver output signal to generate a control voltage which is applied as a bias voltage to the oscillator tube of the receiver. The biasing circuit usually includes a high-impedance resistor provided to minimize power dissipation in the circuit. However, it is found that this high-impedance resistor has a tendency to develop excessive bias voltages during periods of oscillation and intermittently block the receiver circuit. In some installations this tendency towards blocking may be objectionable.

The invention proposes a new type of control system which is peculiarly adapted to superregenerative receivers in which the characteristic quenching action is provided by a periodic quench voltage. The new arrangement takes advantage of the fact that variations in the amplitude or frequency characteristics of the quench voltage produce corresponding variations in the band-width and sensitivity characteristics of the receiver and accomplish the desired control by suitably varying either, or both, of the amplitude and frequency characteristics of the quench voltage. This arrangement presents decided advantages over those of the prior art referred to above. In the first place, when utilized as a sensitivity control, it may be arranged to obviate the undesirable blocking tendency, referred to above, which is inherent in certain prior art arrangements. Furthermore, it affords a band-width control which is less complicated and expensive than those of the prior art.

It is an object of the invention, therefore, to provide an improved control arrangement for controlling an operating characteristic of a superregenerative receiver and which avoids one or more of the above-mentioned limitations of prior art arrangements.

It is another object of the invention to provide an improved control arrangement for controlling an operating characteristic of a superregenerative receiver through a control of the receiver quenching action.

It is still another object of the invention to provide an improved control arrangement for a

superregenerative receiver which is effectively isolated from the signal-translating portions thereof.

In accordance with the invention, a superregenerative receiver including an arrangement for controlling a predetermined operating characteristic thereof comprises a regenerative oscillatory circuit and means for supplying to the oscillatory circuit a periodic quench voltage providing superregeneration and having a characteristic which is effective to determine the above-mentioned operating characteristic of the receiver. The receiver includes means for deriving a signal having a characteristic which varies with an operating condition of the receiver and means responsive to this signal for deriving a control effect. Additionally, the receiver has means for utilizing the control effect to adjust the characteristic of the quench voltage so as to control the aforesaid operating characteristic of the receiver.

For a better understanding of the present invention, together with other and further objects thereof, reference is had to the following description taken in connection with the accompanying drawing, and its scope will be pointed out in the appended claims.

In the drawing, Fig. 1 is a schematic representation of a superregenerative receiver embodying the present invention; Fig. 2 comprises graphs which illustrate alternative operating characteristics of a portion of the Fig. 1 arrangement; Fig. 3 is a schematic representation of a superregenerative receiver embodying the invention in modified form; while Fig. 4 is a schematic circuit diagram of a wave-signal transpondor system including the invention.

Referring now more particularly to Fig. 1, the superregenerative receiver there represented has a linear mode of operation and comprises a regenerative oscillatory circuit including a vacuum tube 10 and a frequency-determining circuit provided by a variable inductor 11 and a condenser C. Condenser C is shown in broken-line construction since it may be comprised in whole, or in part, of the distributed capacitance of inductor 11 and the interelectrode capacitance of the anode and control electrodes of tube 10. The frequency-determining circuit is coupled to the anode of tube 10 through a coupling condenser 12 and has a direct wire connection to the control electrode thereof, the mid-tap of inductor 11 and the cathode of tube 10 being grounded to complete the regenerative oscillatory circuit. There is also coupled to the anode and cathode of tube 10 means for supplying to the regenerative circuit a periodic quench voltage, providing superregeneration and having a characteristic which is effective to determine a predetermined operating characteristic of the receiver. This means comprises a radio-frequency choke 13 and the secondary winding of an iron-core transformer 14, by-passed for radio-frequency currents by a condenser 15. The primary winding of transformer 14 is damped by a resistor 16 and constitutes the load circuit of a pentagrid tube 17. The cathode, first and second control electrodes of tube 17 function, respectively, as the cathode, control electrode and anode of a quench-frequency oscillation generator 18 which produces a periodic quench voltage of rectangular wave form and of a frequency which is low with reference to the operating frequency of the regenerative oscillatory circuit but high with reference to the modulating frequencies of the signals to be received. Oscillation generator 18 is of the well-

known tuned-plate type having a tuned circuit including an inductor 19 and a condenser 20 coupled to its anode electrode. In the control electrode-cathode circuit of generator 18 there are a grid-stabilizing resistor 21, an inductor 22 inductively coupled with inductor 19 and a biasing arrangement comprising the parallel combination of a condenser 23 and a resistor 24. Operating potentials are applied to tube 17 from sources of space current indicated +B and +Sc.

The superregenerative receiver also includes means, specifically a detector system, for deriving from the regenerative oscillatory circuit an output signal having an amplitude characteristic determined by the operating conditions of the receiver. The detector system consists of a diode detector 30 coupled to the frequency-determining circuit of the receiver through a coupling condenser 31 and having as a load circuit a radio-frequency choke 32 and a resistor 33, by-passed for radio-frequency currents by a condenser 34. The output signal of the detector may be supplied to any suitable utilizing circuit, as indicated by the arrow 35. This output signal is also supplied to a unit 40, comprising means responsive thereto for deriving a control effect. Unit 40 includes an amplifier 41 of one or more stages having an input circuit coupled to resistor 33 and having one or more selector circuits arranged to have a pass-band characteristic, as represented by curve a of Fig. 2. From this curve it will be apparent that the amplifier has a maximum response to applied signal components which have a frequency f_q corresponding to the quenching frequency of the receiver, that is, the frequency of the applied quench voltage. To the output circuit of amplifier 41 is coupled a rectifier 42 of conventional construction. A control effect or voltage of negative polarity is derived in the output circuit of rectifier 42 and applied to a control electrode of pentagrid tube 17, this control electrode providing means for utilizing the control effect to adjust a characteristic of the quench voltage so as to control an operating characteristic of the receiver. An antenna-ground system 50 is provided for the receiver and is coupled to the frequency-determining circuit thereof by way of an inductor 51.

In considering the operation of the described receiver, it will be assumed initially that no signals are intercepted by antenna system 50. For this no-signal or quiescent operating condition, the receiver has predetermined band-width and sensitivity characteristics determined largely by the amplitude and frequency characteristics of the applied quench voltage, but also determined by such factors as the characteristics of vacuum tube 10 and its associated frequency-determining circuit. Oscillations are periodically produced in the receiver circuit under the influence of the applied quench voltage in accordance with the characteristic operation of a superregenerative circuit. These oscillations have a frequency corresponding to the operating frequency of the regenerative oscillatory circuit and a relatively low amplitude as determined by the operating characteristics of the receiver and the receiver noise signals which, for the quiescent condition under consideration, initiate the oscillations in successive quench cycles. The generated oscillations are detected by detector 30, producing across resistor 33 a low-amplitude periodic-signal voltage. This signal voltage has a frequency component corresponding to the frequency of the quench voltage and includes components harmonically

related to the quench frequency, as well as components corresponding to the noise signals of the receiver circuit. The quench-frequency component thereof is translated through amplifier 41 and rectifier 42 of unit 40, producing in the output circuit of rectifier 42 a control voltage having a magnitude determined by the amplitude of the quiescent signal output of the receiver. The control voltage is applied with negative polarity to a control electrode of pentagrid tube 17 to control the transconductance thereof and determine the amplitude of the applied quench voltage.

The circuit arrangements of unit 40 are adjusted so that under normal conditions of operation the amplitude of the applied quench voltage is such as to establish a predetermined band width and optimum sensitivity of the receiver. If a change in the operating conditions of the receiver causes the amplitude of the quiescent signal output thereof to be increased, indicating an increased sensitivity, the signal input to unit 40 is increased proportionately and results in a similar increase in the negative-polarity control voltage obtained from rectifier 42. This increase in the control voltage as applied to pentagrid tube 17 reduces the amplitude of the applied quench voltage so as to restore the sensitivity of the receiver to the desired optimum value. Conversely, a decrease in the amplitude of the quiescent signal output reduces the magnitude of the control voltage and increases the amplitude of the applied quench voltage to restore optimum sensitivity. Thus, with the described arrangement, the sensitivity characteristic of the receiver is maintained at a desired level through a control of the amplitude characteristic of the quench voltage. The band-width characteristic of the receiver, which varies directly with variations in the amplitude of the quench voltage, may not be maintained constant in this arrangement since the amplitude of the quench voltage is adjusted to compensate for any change in operating conditions which causes the quiescent signal output of the receiver to deviate from a desired signal level.

Now it will be assumed that a pulse-modulated radio-frequency signal is intercepted by antenna system 50. In general, this signal will have a high intensity with reference to the noise signals in the receiver circuit so that the oscillations generated in each quench cycle occurring within the duration of a received pulse have a relatively high amplitude. During the intervals which intervene between pulses of the received signal, the output signal of detector 30 comprises the low-amplitude quiescent signal described above. The resulting output signal of the receiver, including both the high-amplitude and low-amplitude signal components, is supplied to the utilizing circuit which may include suitable means, such as an amplitude-selective arrangement, for responding only to the high-amplitude components which correspond to the pulses of the received signal. This output signal is also applied to unit 40 for controlling the operating characteristics of the receiver. However, where the quenching frequency is very high with reference to that of the modulating frequency of the received signal, the high-amplitude components appear at such a low repetition frequency as to have substantially no effect on the control voltage derived in unit 40 which responds primarily to the quiescent signal output of the receiver to control the band width and sensitivity characteristics, in the manner described above.

If desired, unit 40 may have a pass-band char-

acteristic, as represented by curve b of Fig. 2, in installations where the receiver is to receive pulse-modulated signals. In such a case, unit 40 rejects the quench-frequency components of the quiescent signal output of the receiver and derives the desired control voltage in response to the noise-signal components of the quiescent signal. The operation of unit 40 in utilizing these signal components to control the band-width and sensitivity characteristics of the receiver is substantially as described above.

In the reception of continuous-wave signals it is advantageous to include selector circuits in unit 40 which have a pass-band characteristic as represented by curve a of Fig. 2. In this case, the control arrangement functions in a manner analogous to automatic volume control arrangements to maintain the signal output of detector 30 within a relatively narrow amplitude range for a wide range of received signal amplitudes.

The control circuits in the Fig. 1 arrangement are effectively isolated from the signal-translating portions of the receiver which, as pointed out above, is especially desirable for receivers of the superregenerative type. Additionally, the coupling circuits which couple tube 10 to the frequency-determining circuit and through which the quench voltage is applied to the regenerative circuit have an impedance which is substantially lower than the impedance of vacuum tube 10 at frequencies less than that of the quench voltage. This also is a particularly desirable feature inasmuch as it obviates the undesirable blocking tendency of certain prior art receiver circuits, mentioned above, which include a high-impedance bias resistor in the control electrode-cathode circuit of the oscillator tube.

The arrangement of Fig. 3 represents a superregenerative receiver which is generally similar to that of Fig. 1, but includes a modified control arrangement in accordance with the invention which is more flexible than that of Fig. 1. Corresponding elements of these receivers are identified by like reference numerals primed. The control arrangement of Fig. 3 comprises a capacitive-type reactance-tube circuit for controlling the operating frequency of the quench-frequency oscillator 18', thereby to control the frequency characteristic of the generated quench voltage. This circuit includes a vacuum tube 25 having an output circuit which is coupled to the anode-cathode circuit of generator 18'. A condenser 26 provides a capacitive feed-back path between the anode and control electrodes of tube 25. An inductor 27 and shunt-connected resistor 28 are included in the control electrode-cathode circuit of tube 25 so that the feed-back voltage has a quadrature-phase relation with reference to that of the anode-cathode circuit voltage. Additionally, the load circuit of rectifier 42' included in unit 40' comprises a pair of parallel voltage-dividing resistors 43 and 44, center tapped to ground so that control voltages of opposite polarities may be obtained from each. For convenience of explanation, the polarity of the control voltages with reference to ground is indicated on the drawing. A voltage tap 45 associated with resistor 43 derives one control voltage which is applied to the reactance tube 25 to control the operating frequency of oscillator 18'. A similar tap 46 associated with resistor 44 derives a second control voltage which is applied to a control electrode of pentagrid tube 17', as in the Fig. 1 arrangement, to control the amplitude of the quench volt-

In considering the operation of the control arrangement of Fig. 3, it will be assumed that no signals are intercepted by antenna 50'. Unit 40' selects a portion of the quiescent signal output of the receiver which is rectified in rectifier 42', producing control voltages across resistors 43 and 44. Taps 45 and 46 select control voltages for application to reactance tube 25 and pentagrid tube 17', respectively, to control the operating characteristics of the receiver by varying the frequency and amplitude characteristics of the quench voltage. Taps 45 and 46 are adjusted so as to effect predetermined relative variations of the band-width and sensitivity characteristics of the receiver with variations in amplitude of the quiescent signal output. The adjustments of these taps may be determined from the following considerations.

It may be shown that like variations in the amplitude and frequency of the quench voltage are effective to vary the band-width characteristic of the receiver in the same sense, but they vary the sensitivity characteristic thereof in opposite senses. More specifically, an increase in either the amplitude or the frequency of the quench voltage causes the receiver to have a greater band width, but an increase in the amplitude of the quench voltage increases the receiver sensitivity, while an increase in the frequency decreases the sensitivity. Therefore, through suitable adjustments of taps 45 and 46, control voltages may be derived from unit 40' of such relative magnitudes and polarities as to effect any desired relative variation of the receiver band-width and sensitivity characteristics with variations in amplitude of the quiescent signal output. For example, the band width may be maintained substantially constant by adjusting taps 45 and 46 so that an increase in the amplitude of the quiescent signal output produces a decrease in the amplitude of the quench voltage and a related increase in the frequency of the quench voltage.

In the reception of pulse-modulated or continuous-wave signals the receiver of Fig. 3 operates in a manner similar to that of the receiver represented in Fig. 1. This operation will be apparent from the foregoing description.

In Fig. 4 there is represented a wave-signal transpondor system including a receiver constructed in accordance with the teaching of the present invention. As used in this specification, the term "transpondor system" is intended to describe a wave-signal translating system which includes a receiver and a transmitter so arranged that a predetermined answer or reply signal is transmitted in response to a received interrogating signal, the reply and interrogating signals preferably comprising radiant-energy wave signals. For convenience of explanation, the system is illustrated as a radio beacon for transmitting direction-finding information to interrogating aircraft. The receiver portion of the transpondor system consists of a superregenerative receiver having a linear mode of operation. This receiver comprises a vacuum tube 60 and a frequency-determining circuit provided by a variable inductor 61 and a condenser C''. Condenser C'' is shown in broken-line construction since it may be comprised in whole, or in part, of the distributed capacitance of inductor 61 and the interelectrode capacitance of the anode and control electrodes of tube 60. The frequency-determining circuit is damped by a resistor 62 and is coupled to the anode and control electrodes of

tube 60 by way of coupling condensers 63 and 64, respectively. The cathode circuit of tube 60 includes a radio-frequency choke 65 and a resistor 66. A biasing circuit is coupled to the control electrode thereof, including a radio-frequency choke 67, a resistor 68 and a source of bias voltage indicated -C. A source of space current indicated +B is coupled to the anode of tube 60 through a radio-frequency choke 79 and a quench voltage providing superregeneration is applied thereto from a quench-frequency oscillator 69 by way of vacuum-tube amplifier 71 coupled to oscillator 69 through a coupling condenser 70. The load circuit of amplifier 71 consists of a tuned circuit, including an inductor 72 and a condenser 73, tuned to the frequency of the quench voltage and highly damped by a resistor 74. A coupling condenser 89 couples the load circuit of amplifier 71 to the control electrode of tube 60.

A detector 75 for deriving an output signal from the regenerative oscillatory circuit is coupled thereto through a condenser 76. The load circuit of detector 75 comprises a radio-frequency choke 77 and a resistor 78. A control arrangement 80 is coupled to the load circuit of detector 75 and includes an amplifier 81 of one or more stages having an output circuit coupled to a diode rectifier 82 through a coupling condenser 83. Rectifier 82 has a load circuit including a resistor 84 and a control voltage derived therefrom is applied through a resistor 85 to the control electrode of vacuum-tube amplifier 71 for the purpose of controlling the amplitude characteristic of the quench voltage in accordance with variations in amplitude of the output signal of detector 75, thereby to determine and control the sensitivity and band-width characteristics of the receiver. An antenna system 88 is capacitively coupled to the regenerative oscillatory circuit through a condenser 86 and is inductively coupled thereto by means of an inductor 87.

The transmitter portion of the transpondor system likewise comprises a regenerative oscillatory circuit including a vacuum tube 90 having anode and control electrodes which are coupled through condensers 91 and 92, respectively, to the above-described frequency-determining circuit which is common to both the receiver and transmitter units. The cathode circuit of tube 90 includes a radio-frequency choke 93 and a time-constant circuit provided by the parallel arrangement of a condenser 94 and resistor 95. A source of bias voltage -C is applied to the control electrode of tube 90 through a radio-frequency choke 96 and is selected of such magnitude as normally to block oscillations in the transmitter.

A pulse generator 97, having an input circuit coupled to load resistor 78 of detector 75 and having an output circuit coupled to the anode of transmitting tube 90 through a radio-frequency choke 98, permits control of the transmitter operation under the influence of the receiver, as described more particularly herein-after. Generator 97 may comprise a conventional trigger circuit such as a single-pulse relaxation oscillator which, when keyed, generates a single pulse of unidirectional potential having a substantially rectangular wave form.

In considering the operation of the described transpondor system, it will be assumed initially that no signals are being intercepted by the antenna system 88. For the assumed operating conditions, the quiescent signal output of the receiver is detected in detector 75 and applied to

unit 80 for the purpose of developing a control voltage having a magnitude which varies in accordance with the amplitude variations of the quiescent signal output of the receiver. This control voltage is applied to amplifier 71 to control the amplitude characteristic of the applied quench voltage so as to effect a desired control of both the sensitivity and band-width characteristics of the receiver in the manner fully described above. The quiescent signal output of the receiver is also applied to generator 97. However, this output signal, which has a low-amplitude level, is ineffective to trigger the generator so that the transmitter tube 90 remains blocked during quiescent operating intervals.

Let it be assumed now that an aircraft desiring direction-finding information from the transpondor transmits thereto an interrogating signal comprising a pulse-modulated radio-frequency signal. As indicated above, an output signal of relatively high amplitude is derived in the load circuit of detector 75 in quench cycles occurring within the interval of the received pulse of the interrogating signal. This high-amplitude signal keys generator 97 for a single cycle and applies a pulse of unidirectional potential to the anode-cathode circuit of tube 90 of sufficient magnitude to overcome the normal holding voltage applied to the control electrode thereof and initiate oscillations in the transmitter. As the oscillations of tube 90 continue, condenser 94 included in its cathode circuit becomes charged, raising the cathode potential thereof, tending to terminate transmission. The value of condenser 94 is so chosen that the transmitted pulse generated by tube 90 and transmitted through the common antenna system 88 has a predetermined pulse duration, preferably equal to that of the received pulses of the interrogating signal. Thus, in response to a received interrogating signal, the transpondor system transmits a reply signal comprising pulses of radio-frequency energy having the same duration and pulse-repetition frequency as the received signal. The inquiring aircraft is able to obtain bearing indications from the transmitted signal or, if desired, the transmitted signal may be coded to transmit desired direction-finding information. Suitable coding arrangements for this purpose are fully disclosed in copending application Serial No. 516,394, filed December 31, 1943, in the name of Bernard D. Loughlin and assigned to the same assignee as the present invention.

In the arrangements described above, the quench voltage has been defined as having a substantially rectangular wave form. It will be understood that other wave forms may be utilized if desired. For example, quench voltages of sinusoidal wave form are commonly employed in the art. Likewise, in controlling a characteristic of the quench voltage, it is not necessary that the described control arrangement be adjusted to maintain a given sensitivity in the receiver. As indicated above, the control feature may be utilized to maintain a given band width or, through the use of the Fig. 3 control arrangement, a desired relative control of band width and sensitivity may be obtained. Also, the control voltage need not necessarily be derived in response to the output signal of the regenerative oscillatory circuit. For example, in utilizing the control arrangement primarily to control the band width of the receiver, the control voltage may be derived in response to the intensity of a received desired signal. In such a case, the control voltage

5 may be developed from the signal output of an amplifier stage intermediate the antenna system and the regenerative circuit, or from the signal output of an auxiliary antenna system. In any case, the control voltage is to be derived from a signal having a characteristic which varies with an operating condition of the receiver.

10 It will also be understood that units 40, 40' and 80 may include arrangements which permit the receiver to translate pulse-modulated received signals having pulse-repetition frequencies that vary over a wide frequency range. One such arrangement is disclosed in copending application Serial No. 521,926, filed concurrently with this application, in the name of John A. Hansen and Bernard D. Loughlin and assigned to the same assignee as the first invention.

15 The receiver circuits described above have a linear mode of operation but may operate with a logarithmic mode if desired. In such a case, an integrating circuit may be included for deriving an output signal having a characteristic, such as an amplitude characteristic, which is determined by the operating characteristics of the receiver. It will be apparent that the teaching of the invention is equally applicable to such receiver circuits.

20 25 30 35 While there have been described what are at present considered to be the preferred embodiments of this invention, it will be obvious to those skilled in the art that various changes and modifications may be made therein without departing from the invention, and it is, therefore, aimed in the appended claims to cover all such changes and modifications as fall within the true spirit and scope of the invention.

35 What is claimed is:

40 45 50 55 1. A superregenerative receiver including an arrangement for controlling a predetermined operating characteristic thereof comprising, a regenerative oscillatory circuit, means for supplying to said circuit a periodic quench voltage providing superregeneration and having a characteristic effective to determine said operating characteristic of said receiver, means for deriving a signal having a characteristic varying with an operating condition of said receiver, means responsive to said signal for deriving a control effect, and means for utilizing said control effect to adjust said characteristic of said quench voltage so as to control said operating characteristic of said receiver.

60 65 70 75 2. A superregenerative receiver including an arrangement for controlling a predetermined operating characteristic thereof comprising, a regenerative oscillatory circuit, means for supplying to said circuit a periodic quench voltage providing superregeneration and having a characteristic effective to determine said operating characteristic of said receiver, means for deriving from said circuit an output signal having a characteristic determined by said operating characteristic of said receiver, means responsive to said output signal for deriving a control effect, and means for utilizing said control effect to adjust said characteristic of said quench voltage so as to control said operating characteristic of said receiver.

70 75 80 85 3. A superregenerative receiver including an arrangement for controlling a predetermined operating characteristic thereof comprising, a regenerative oscillatory circuit, means for supplying to said circuit a periodic quench voltage providing superregeneration and having a characteristic effective to determine said operating characteristic of said receiver, means for deriving a

signal having an amplitude characteristic varying with an operating condition of said receiver, means responsive to the amplitude of said signal for deriving a control effect, and means for utilizing said control effect to adjust said characteristic of said quench voltage so as to control said operating characteristic of said receiver.

4. A superregenerative receiver including an arrangement for controlling a predetermined operating characteristic thereof comprising, a regenerative oscillatory circuit, means for supplying to said circuit a periodic quench voltage providing superregeneration and having a characteristic effective to determine said operating characteristic of said receiver, means for deriving a signal having an amplitude characteristic varying with an operating condition of said receiver, means for detecting the amplitude of said signal to derive a control effect, and means for utilizing said control effect to adjust said characteristic of said quench voltage so as to control said operating characteristic of said receiver.

5. A superregenerative receiver including an arrangement for controlling a predetermined operating characteristic thereof comprising, a regenerative oscillatory circuit, means for supplying to said circuit a periodic quench voltage providing superregeneration and having an amplitude characteristic effective to determine said operating characteristic of said receiver, means for deriving a signal having a characteristic varying with an operating condition of said receiver, means responsive to said signal for deriving a control effect, and means for utilizing said control effect to adjust said amplitude characteristic of said quench voltage so as to control said operating characteristic of said receiver.

6. A superregenerative receiver including an arrangement for controlling a predetermined operating characteristic thereof comprising, a regenerative oscillatory circuit, means for supplying to said circuit a periodic quench voltage providing superregeneration and having a frequency characteristic effective to determine said operating characteristic of said receiver, means for deriving a signal having a characteristic varying with an operating condition of said receiver, means responsive to said signal for deriving a control effect, and means for utilizing said control effect to adjust said frequency characteristic of said quench voltage so as to control said operating characteristic of said receiver.

7. A superregenerative receiver including an arrangement for controlling the band-width and sensitivity characteristics thereof comprising, a regenerative oscillatory circuit, means for supplying to said circuit a periodic quench voltage providing superregeneration and having a characteristic effective to determine said band-width and sensitivity characteristics of said receiver, means for deriving a signal having a characteristic varying with an operating condition of said receiver, means responsive to said signal for deriving a control effect, and means for utilizing said control effect to adjust said characteristic of said quench voltage so as to control said band width and sensitivity characteristics of said receiver.

8. A superregenerative receiver including an arrangement for controlling a predetermined operating characteristic thereof comprising, a regenerative oscillatory circuit, means for supplying to said circuit a periodic quench voltage providing superregeneration and having amplitude and frequency characteristics which are indi-

vidually effective to control said operating characteristic of said receiver, means for deriving a signal having a characteristic varying with an operating condition of said receiver, means responsive to said signal for deriving a control effect, and means for utilizing said control effect individually to control said amplitude and frequency characteristics of said quench voltage so as to control said operating characteristic of said receiver.

10 9. A superregenerative receiver including an arrangement for controlling the band-width and sensitivity characteristics thereof comprising, a regenerative oscillatory circuit, means for supplying to said circuit a periodic quench voltage
15 providing superregeneration and having amplitude and frequency characteristics which control said band-width characteristic of said receiver in the same sense and which control said sensitivity characteristic thereof in opposed senses,
20 means for deriving a signal having a characteristic varying with an operating condition of said receiver, means responsive to said signal for deriving a control effect, and means for utilizing said control effect individually to control said
25 amplitude and frequency characteristics of said quench voltage so as to control said band-width and sensitivity characteristics of said receiver.

10. A superregenerative receiver including an arrangement for controlling the band-width and sensitivity characteristics thereof comprising, a regenerative oscillatory circuit, means for supplying to said circuit a periodic quench voltage providing superregeneration and having amplitude and frequency characteristics which control 35 said band width of said receiver in the same sense and which control said sensitivity characteristic thereof in opposed senses, means for deriving a signal having a characteristic varying with an operating condition of said receiver, means responsive to said signal for deriving a control effect having a magnitude determined by said characteristic of said signal, and means for utilizing said control effect individually to control 40 said amplitude and frequency characteristics of 45 said receiver with variations of said characteristic of said signal.

11. A superregenerative receiver including an arrangement for controlling the band-width and sensitivity characteristics thereof comprising, a regenerative oscillatory circuit, means for supplying to said circuit a periodic quench voltage providing superregeneration and having amplitude and frequency characteristics which control said band-width characteristic of said receiver in the same sense and which control said sensitivity characteristic thereof in opposed senses, means for deriving a signal having a characteristic varying with an operating condition of said receiver, means responsive to said signal for deriving a control effect having a magnitude determined by said characteristic of said signal, and means for utilizing said control effect individually to control said amplitude and frequency characteristics of said quench voltage so as to effect predetermined relative variations of said band-width and sensitivity characteristics of said receiver with variations of said characteristic of said signal.

12. A superregenerative receiver including an arrangement for controlling the band-width and sensitivity characteristics thereof comprising, a regenerative oscillatory circuit, means for supplying to said circuit a periodic quench voltage

providing superregeneration and having amplitude and frequency characteristics which control said band-width characteristic of said receiver in the same sense and which control said sensitivity characteristic thereof in opposed senses, means for deriving a signal having a characteristic varying with an operating condition of said receiver, means responsive to said signal for deriving at least two control effects individually having a magnitude determined by said characteristic of said signal, and means for utilizing one of said control effects to control said amplitude characteristic of said quench voltage and for utilizing another of said control effects to control said frequency characteristic of said voltage, said control effects having such relative magnitudes as to effect predetermined relative variations of said band-width and sensitivity characteristics of said receiver with variations of said characteristic of said signal.

13. A superregenerative receiver including an arrangement for controlling the band-width and sensitivity characteristics thereof comprising, a regenerative oscillatory circuit, means for supplying to said circuit a periodic quench voltage providing superregeneration and having amplitude and frequency characteristics which control said band-width characteristic of said receiver in the same sense and which control said sensitivity characteristic thereof in opposed senses, means for deriving a signal having a characteristic varying with an operating condition of said receiver, means responsive to said signal for deriving at least two control voltages individually having a magnitude determined by said characteristic of said signal, and means for utilizing one of said control voltages to control said amplitude characteristic of said quench voltage and for utilizing another of said control voltages to control said frequency characteristic of said quench voltage, said control voltages having such relative magnitudes and polarities as to effect predetermined relative variations of said band-width and sensitivity characteristics of said receiver with variations of said characteristic of said signal.

14. A superregenerative receiver including an arrangement for controlling a predetermined operating characteristic thereof comprising, a regenerative oscillatory circuit, means including an oscillation generator for supplying to said circuit a periodic quench voltage providing superregeneration and having a characteristic effective to determine said operating characteristic of said receiver, means for deriving a signal having a characteristic varying with an operating condition of said receiver, means responsive to said signal for deriving a control voltage, means for applying said control voltage to said generator so to vary said characteristic of said quench volt-

age as to control said operating characteristic of said receiver.

15. A superregenerative receiver including an arrangement for controlling a predetermined operating characteristic thereof comprising, a regenerative oscillatory circuit, means including an oscillation generator and a vacuum-tube amplifier for supplying to said circuit a periodic quench voltage providing superregeneration and having an amplitude characteristic effective to determine said operating characteristic of said receiver, means for deriving a signal having a characteristic varying with an operating condition of said receiver, means responsive to said signal for deriving a control voltage, means for applying said control voltage to said amplifier to adjust said amplitude characteristic of said quench voltage so as to control said operating characteristic of said receiver.

16. A superregenerative receiver including an arrangement for controlling a predetermined operating characteristic thereof comprising, a regenerative oscillatory circuit, means including an oscillation generator for supplying to said circuit a periodic quench voltage providing superregeneration and having a frequency characteristic effective to determine said operating characteristic of said receiver, means for deriving a signal having a characteristic varying with an operating condition of said receiver, means responsive to said signal for deriving a control effect, and reactance-tube means for utilizing said control effect to adjust the operating frequency of said generator so as to control said operating characteristic of said receiver.

17. A superregenerative receiver including an arrangement for controlling a predetermined operating characteristic thereof comprising, a regenerative oscillatory circuit including vacuum-tube means and a frequency-determining circuit, means for supplying to said oscillatory circuit a periodic quench voltage providing superregeneration and having a characteristic effective to determine said operating characteristic of said receiver, said oscillatory circuit and said quench-voltage supply means including only coupling circuits having an impedance which is substantially lower than the impedance of said vacuum-tube means at frequencies less than that of said quench voltage for coupling said vacuum-tube means to said frequency-determining circuit and for applying said quench voltage thereto, means for deriving a signal having a characteristic varying with an operating condition of said receiver, means responsive to said signal for deriving a control effect, and means for utilizing said control effect to adjust said characteristic of said quench voltage so as to control said operating characteristic of said receiver.
